B. STEMBER

BAG FASTENER

Filed Feb. 14, 1928

INVENTOR.

Bernard Stember
BY
Felix C. Fischer
ATTORNEY

UNITED STATES PATENT OFFICE.

BERNARD STEMBER, OF NEW YORK, N. Y.

BAG FASTENER.

Application filed February 14, 1928. Serial No. 254,207.

This invention relates to bag fasteners, and more particularly to devices for preventing the accidental opening of ladies' hand bags and the like.

5 One of the objections to the snap fasteners commonly used on ladies' hand bags is that such fasteners become loose with constant use; their action not being positive, consequently it is not uncommon to see women 10 upon the public highway unconscious of the fact that the worn fastener on their hand bags has allowed the bag to open, exposing the contents thereof to pickpockets, etc.

15 An object of this invention is to provide a safety device for bag fasteners, so constructed that accidental opening of a bag will be prevented.

A further object is to provide a safety bag 20 fastener which will not lose its effectiveness by repeated use.

A further object is to provide a bag fastener having elements simple in structure and so designed as to eliminate the possibility of accidental breaking.

A further object is to provide a bag fastener which is effective as a safety device, yet pleasing in appearance and appealing to the esthetic sense.

30 These and other objects are attained by the novel construction, combination and arrangement of parts hereinafter described and shown in the accompanying drawing, constituting a material part of this disclosure, and in which:

Figure 1 is a perspective view showing the fastener mounted on a bag frame.

Figure 2 is a fragmentary perspective view showing the safety device in an open 40 position.

Figure 3 is a cross-sectional view showing the manner in which the fastener is mounted on a bag frame.

Figure 4 is a longitudinal sectional view 45 showing further details of the mounting of the fastener on a bag frame.

Figure 5 is a fragmentary perspective view of a modified form showing the fastener embracing the frame elements and 50 having thereto attached a mirror or the like.

Referring in greater detail to the drawings, a bag frame is shown to be composed of two channelled members 10 and 12 hinged together at 11. Mounted on the channel 55 member 10 is a lug 14 having its inner side

inclined outwardly so that a cap 15 will readily cam thereover.

Positioned in the channel of member 12 is a torsional spring 16 having a flattened end 17 which contacts with the sides of the frame members to limit rotation of the spring, the other end of the spring being flattened and surrounded by a loop 18, which has a horizontal portion permanently fixed to the cap 15 and an aperture through which a plunger 19 extends. The plunger 19 is normally forced upward by a coiled compression spring 20 which contacts with disc 21 on the plunger and the base of the tubular portion 15' of the cap 15.

A pin 22 passes diametrically through the tubular member 15' and pivoted upon it, is the flattened portion 23 of a rod 24. The tubular member 15' is provided with a transverse slot 25 to allow unobstructed movement of the flattened tenon 23 through an angle of 180°. The inner end of the pin 22 is flat and contacts with the disc 21.

Attached to the opposite extremity of the rod 24 is a cylindrical cup member 26, adapted to encircle upstanding projections 27 and 28, fixedly mounted on channel members 10 and 12, respectively.

When it is desired to close a bag equipped with this fastener, the cap 15 is snapped over the lug 14, and the rod 24 is pivoted into a horizontal position so that the cylindrical cup member 26 encompasses the projections 27 and 28, and accidental opening of the bag is thus prevented.

The manner in which the rod 24 is positioned enables the attachment thereto of a mirror (Figure 5) which may pass through slots in the frame members and be concealed from view when rod 24 is in the horizontal position as shown in Figure 1.

Instead of using the projections 27 and 28, the cylindrical cup member 26 may be provided with a pair of diametrically opposite slots cut in the periphery of and extending to its free edge (Figure 5). With such a structure, the cup member 26 will directly embrace the outer edges of frame members 10 and 12 and prevent accidental opening of the bag.

It will be seen that the rod 24 may be rotated through an angle of 180° and that it will be resiliently held in two horizontal positions and one vertical position. This arrangement eliminates the possibility of acci-

dentially bending or breaking the structure as would be the case were the rotation limited to 90°.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:—

15. 1. A fastening device for a bag having a pair of frame members hinged to each other, said device comprising a spring controlled cap mounted on one frame member and adapted to snap over a lug on the other frame member to close the bag, a rod pivotally connected at one end to said cap, and provided with means at its opposite end to have locking engagement with said frame members.
20. 2. A fastening device for a bag having a pair of frame members hinged to each other, said device comprising a spring controlled cap mounted on one frame member and adapted to snap over a lug on the other frame member to close the bag, a pair of projections fixed to said frame members, spaced from the said cap and lug, a rod pivotally connected at one end to said cap, and a cylindrical cup member fixed to the other end of the rod and adapted to encompass said projections to prevent accidental opening of the bag.
25. 3. A bag fastener means for securing one frame member of a bag to another frame member, comprising a pair of projections on said frame members and spaced from said means, a rod pivotally connected at one end to said means, and a cylindrical member fixed

to the opposite end of said rod and adapted to encompass said projections.

4. In combination with a bag fastener, a device for preventing accidental opening of a bag, said device comprising a pair of projections fixed to the frame members of a bag and spaced from said fastener, a member pivotally connected at one end with said fastener and having means at its opposite end to encircle said projections, and means for resiliently holding said member in a horizontal or a vertical position.

5. A bag fastener comprising a pair of projections fixed to adjacent frame members of a bag, a member having means at one end to encircle said projections, means to pivotally connect said member with one of the frame members, and means for resiliently holding said member in a plurality of positions, said member being rotatable through an angle of 180°.

6. A bag fastener comprising a pair of projections positioned side by side, each of said projections being mounted on separate adjacent frame members of a bag, a rod having a cylindrical cup member at one end adapted to encircle said projections, means for pivotally connecting the other end of said rod with one of the frame members, and means for resiliently holding said rod in plurality of positions, said rod being rotatable through an angle of 180°.

7. A bag fastener comprising a pair of projections on adjacent frame members of a bag, a rod having means at one end adapted to encircle said projections, and means for pivotally connecting the other end of said rod with one of the frame members, said rod being rotatable through an angle of 180°.

This specification signed this eighth day of February, 1928.

BERNARD STEMBER.
